UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

TUBE FOR HEAT EXCHANGE DEVICES

Application filed November 20, 1929. Serial No. 408,497.

The invention relates to improvements in heat exchange devices and is herein shown and described as performing the function of a device of this character which is employed 5 to maintain a medium of an internal combustion engine in a cooled condition.

The invention has, among its prime objects, the provision of a construction whereby air which is circulated between the tubes of 10 the radiator to effect a cooling of the circulating medium, is caused to be directed by the tubes into engagement therewith, be agitated thereby and thus facilitate cooling and maintenance of the fluid in a cool condition.

15 It is an object of the invention to construct the fluid conducting passages in a manner to accomplish the advantages just referred to.

Another object of the invention is to form the tubes for the circulating medium in a 20 manner to provide a recessed portion and an extending or protruding tubular portion, the latter forming a fluid passage and to arrange tubes fashioned as above in spaced relation to each other with the projecting or tubular 25 portion of one tube arranged relatively to the recessed portion of an adjacent tube to thereby provide a tortuous path for air passing between the tubes and also to thereby provide means for agitating said air during its travel 30 between said tubes and in addition to provide means for directing said air towards the tubes to thus result in increasing the cooling efficiency of heat exchange devices.

It is another object to combine with fluid 35 passages constructed as above, heat radiating fins, the latter being fashioned to agitate air passing between said fins.

The invention has these and other objects, all of which will be explained in detail and 40 more readily understood when read in conjunction with the accompanying drawing which illustrates one embodiment of which the invention is susceptible, it being obvious that changes and modifications may be 45 resorted to without departing from the spirit of the appended claims forming a part hereof.

In the drawing, Fig. 1 is a front elevation 50 of an automobile radiator constructed according to the invention;

Fig. 2 is a section taken on line 2—2 of Fig. 1, the parts being shown at a slightly enlarged scale;

Fig. 3 is a section taken on line 3—3 of Fig. 1, also slightly enlarged; and

Fig. 4 is a perspective view of the tubes employed in the structure shown in Fig. 1, having heat radiating fins associated therewith.

The embodiment of the invention illustrated in the drawing is shown as being employed in connection with an automobile radiator generally designated 10, however, it is understood that the use of the invention is not limited to radiators employed for this purpose. The radiator shown includes the tanks 11 and 12 having the inlet 13 and the outlet 14, the tanks being connected together by a plurality of vertically arranged fluid tubes or passages 15 which form a communication 70 between the tanks and provide passages for the cooling medium which circulates through the radiator and back to the water jacket of an engine (not shown) with which the radiator is associated.

The structure as shown in Fig. 1 also contemplates the use of parallel horizontally arranged fins 16 which in the present construction are apertured to allow the association thereof with the tubes 15. It is understood that the tubes generally designated 15 are arranged in spaced relation to each other and thus provide a passage permitting air to travel between them.

By referring particularly to Figs. 2 and 85 4, it will be noted that each of the tubes generally designated 15 is fashioned to provide a plurality of longitudinally extending fluid passages 17, 18 and 19 and the recessed portions 20, 21 and 22, the tubular portion 18 90 being arranged at the recess such as 20. It may be here stated that any desired number of projections and recesses may be utilized. It will be noted also that the tubular passages such as 17, 18 and 19 and the recessed 95 portions produce shoulders 23 which form baffles which are provided to engage air passing between the tubes and cause its agitation and thus increase the cooling efficiency of the air.

By again referring to Figs. 3 and 4, it will be seen that the tubular passages form projections and that said projections of one tube are arranged opposite a recess of an adjacent tube and since the tubes generally designated 15 are arranged in spaced relation to each other, a tortuous space is produced between said tubes which will increase the distance which the air is compelled to travel during its passage between said tubes and thus more efficiently cool the circulating or cooling medium contained in the tubular passages such as 17, 18 and 19. It will also be noted that the relative arrangement of the tubes such as 17, 18 and 19 and the recesses of the tubes generally designated 15 cause the air passing through the space between said tubes 15 to be successively directed in opposed directions toward said tubes which will also agitate the air and manifestly increase the cooling effect upon the fluid circulating through the tubular passages such as 17, 18 and 19.

It may here be stated that the tubes generally designated 15 may be formed of a single sheet of relatively thin material which sheet is bent longitudinally intermediate the edges of the material, the free edges thereof being brought together and welded or otherwise secured with each other to form a leak-proof connection at the connected edges thereof. Whereas the tubes 15 are constructed in this manner, it is understood that this particular construction need not be adhered to as various other constructions may be resorted to without departing from the spirit of the invention.

It will be noted by again referring to Fig. 3 that a wall such as 24 of a recess such as 20 projects a slight distance beyond the termination of the side walls of an adjacent tubular passage such as 18 and that this wall 24 is spaced a slight distance from the depressions forming the wall of the recesses such as 21 and 22 which results in providing a relatively narrow space between these portions in which a portion of the cooling medium is contained during circulation, which will thus subject a very thin film of cooling medium to the action of a current of air and thus assist to quickly reduce the temperature of the cooling medium circulating through the radiator at this point.

As before stated, it is contemplated, when found desirable, to associate the fins 16 with tubes 15 constructed as above described and to form said fins to produce means for engaging the air passing between said tubes 15 and cause said air to be turbulated. To this end, the fins 16 are constructed to provide one or more projections and recesses respectively designated 25 and 26 which will engage the air and agitate it. These fins may be provided with a plurality of apertures such as 27 to allow said fins to be

passed endwise along the tubes generally designated 15 to the desired position upon said tubes to which said fins are brazed or soldered in the usual manner.

From the foregoing description of the invention, it is manifest that the construction of the tubes is such that said tubes provide a simple and efficient means for causing air which is introduced between said tubes to be compelled to travel a tortuous path, be agitated and brought into engagement with the sides of the tubes. It is further evident that by constructing said tubes in a manner to provide each tube with a plurality of fluid passages that the cooling medium circulating through a given tube is divided into a plurality of separate streams which will thus cause the temperature of the fluid to be more quickly dissipated. The association of fins with a construction such as this character will increase the cooling efficiency of devices of this character and thus result in producing an effective cooling construction.

Having thus described the invention, what I claim and desire to cover by Letters Patent is:

1. A radiator comprised of a plurality of tubes, each tube having a plurality of fluid passages, one tube being arranged in spaced relation to an adjacent tube, the fluid passages of one tube being arranged relatively to the fluid passages of an adjacent tube to thereby provide means for directing air into contact with tubes defining said space and agitating said air during passage through said space and transversely arranged fins having air agitating means connected with said tubes.

2. A radiator comprised of a plurality of tubes, each tube having a plurality of fluid passages, one tube being arranged in spaced relation to an adjacent tube, the fluid passages of one tube being arranged relatively to the fluid passages of an adjacent tube to thereby provide means for directing air into contact with tubes defining said space and agitating said air during passage through said space and transversely arranged heat radiating strips connected with said tubes, said strips being formed to provide recesses and projections.

In witness whereof, I hereunto subscribe my name this 6th day of November, A. D. 1929.

ARTHUR B. MODINE.
